UNITED STATES PATENT OFFICE.

ROBERT G. HOPKINS, OF SOMERVILLE, MASSACHUSETTS.

DESIGN FOR A TYPE-WRITER RIBBON.

SPECIFICATION forming part of Design No. 28,342, dated March 8, 1898.

Application filed November 12, 1897. Serial No. 658,348. Term of patent 14 years.

To all whom it may concern:

Be it known that I, ROBERT G. HOPKINS, a citizen of the United States, residing at Somerville, in the county of Middlesex and State 5 of Massachusetts, have invented and produced a new and original Design for Type-Writer Ribbons, of which the following is a specification, reference being had to the accompanying drawing, showing the same.

My invention comprises a design for a type-writer ribbon; and it consists of a section of any desired length and of uniform width throughout its length having the texture of a woven cloth or fabric and end sections in 5 the form of tapering extensions or tongues of a smooth texture or surface contrasting with that of the main section.

In the drawing, A represents the interme-

diate section, which is of uniform width throughout and has the usual texture of type- 20 writer ribbons.

B C respectively represent the ends, each of which has a smooth or closely-finished surface contrasting with the coarse surface of the section A and each of which has a tapering extension ending in a loop, b representing the tapering extension of one end, c the tapering extension of the other end, and b' c' the respective loops. 25

What I claim is—

The design for the type-writer ribbon herein shown and described.

ROBERT G. HOPKINS.
